UNITED STATES PATENT OFFICE.

HERBERT M. SMEBY, OF CHICAGO, ILLINOIS.

TELEPHONE COIN-BOX AND HOLDER.

1,321,156.

Specification of Letters Patent. Patented Nov. 11, 1919.

Application filed March 6, 1917. Serial No. 152,775.

To all whom it may concern:

Be it known that I, HERBERT M. SMEBY, a citizen of the United States, residing at Chicago, in the county of Cook and State of Illinois, have invented certain new and useful Improvements in Telephone Coin-Boxes and Holders, of which the following is a specification.

Coin boxes for the payment of telephone calls are in common use, and such boxes are usually placed on the wall or in a position which must be convenient to the instrument. As ordinarily arranged, a stand or holder must be provided adjacent to the coin box for supporting the telephone. In accordance with the present invention I provide a combined coin box and telephone stand or holder, which will obviate the necessity of any additional supports for the instrument. The object of this invention will be readily apparent. It will be seen that it provides means for supporting the telephone on or in connection with the coin box, where it will be convenient for use, and such arrangement will be simple and economical in construction and very convenient in operation.

In the accompanying drawings illustrating this invention:

Figure 1 is a front view of a combined coin box and holder embodying a preferred form of the invention;

Fig. 2 is a side view thereof, with parts broken away to show the details of construction;

Fig. 3 is a plan view; and

Fig. 4 is a side view showing a slightly modified form of construction.

Any ordinary or preferred mechanism may be used in the coin box, but such mechanism forms no part of the present invention. In accordance with my invention I provide a coin box such as the box 5 shown in the accompanying drawings, with a holder 6 formed integrally with the top thereof. The holder 6 is made in any suitable shape to conform with the base of the telephone 7, and is preferably provided with an upwardly extending flange or projection 8, which may extend entirely around the

same or may be otherwise formed in order 50 to prevent the lateral displacement of the telephone.

The telephone and coin box may both be used in the ordinary manner, the phone being left in the holder while it is being used, 55 or temporarily removed therefrom if desired. It will be seen that by means of this arrangement, as soon as the coin box is installed, a holder is provided for the telephone, which will occupy practically no additional space and therefore the set may be placed in limited or out of the way places, 60 where a desk or table could not be used. Furthermore, this holder will prevent the necessity of leaving the telephone standing 65 on the floor, as is usually the case when a telephone is first installed in an office or apartment.

My improved holder may also be made separately from the coin box and attached 70 thereto in any convenient manner, as is shown, for instance, in Fig. 4. In this case the coin box 9 is provided with a holder 10, which is made separately, and is held in position by means of screws or bolts 11. In 75 this instance the holder is shown extending back over the top of the plate or board 12, which is commonly used for supporting the coin box, so that the holder does not project to any considerable distance at the front 80 of the box. In order to avoid any electrical interference, the holder 10 may be insulated from the box by means of the insulating strips 13, which are inserted between the holder and the box, it being understood that 85 the screws are also insulated from the holder, or, if desired, the holder 10 may be made of rubber, fiber or other insulating material, although the holder may be made of any suitable material. It will of course be understood that sufficient room will be left below the holder for the insertion of the coin in the coin slot 14 or in any projecting coin receiving device which may be used on the 90 box.

It will be noted that changes may be readily made in the details of construction or arrangement of parts of this invention,

without departing from the scope thereof, and therefore I do not wish to limit myself to the exact construction or arrangement herein shown and described, except as set forth in the following claims, in which I claim:

1. The combination with a telephone coin box, of an integrally formed holder comprising a plate formed integrally with the 10 box at the top thereof, with upwardly ex-

tending projections for engagement with the sides of the telephone base.

2. The combination with a telephone coin box, of a substantially circular plate formed integrally therewith, with an upwardly extending flange around the edge thereof, said plate being adapted to receive and support the telephone. 15

HERBERT M. SMEBY.
